UNITED STATES PATENT OFFICE

ROBERT HETHERINGTON, OF SHARON HILL, PENNSYLVANIA

AUTOMATIC THERMOSTATIC CONTROL VALVE

Application filed December 24, 1928. Serial No. 328,261.

My invention relates to thermostatic control valves for supply of water and of other liquids.

The purpose of my invention is to provide 5 immediate control by a thermostatic element which is itself a cut-off valve.

A further purpose is to operate a sensitive 10 thermostatic element directly across a narrow valve inlet opening so that the water flow will be cut off quickly if its temperature be excessive.

A further purpose is to use one of the arms 15 of a U-shaped thermostat as a cut-off for the water flow.

Further purposes will appear in the specification and in the claims.

Because shower baths offer very excellent 20 illustrations of the need and also of the use of my thermostatic valve I have illustrated it in connection with shower baths, notwithstanding that I recognize that my invention is of much broader application than to shower baths merely and can be used for protection not only against temperatures injurious to 25 the person, as in the case of the shower baths, but also to control the temperatures of liquids such as are used in tempering, chemical reactions, cooking operations, etc.

I have preferred to show one general form 30 only of the various forms in which my invention might appear, and to show but two variations of that form, selecting a form which is practical, efficient, inexpensive and very reliable and which at the same time well illustrates the principles of my invention.

Figure 1 is a perspective view of a shower 35 bath equipment embodying my invention.

Figure 1a is a fragmentary view applying 40 the invention to control of the supply to a bank of showers.

Figure 2 is a longitudinal section of a portion 45 of the structure of Figure 1 showing one of my controls.

Figure 3 is a section of Figure 2 taken upon the line 3-3.

Figure 4 is a section similar to Figure 2 50 but showing a variation of the form.

Figure 5 is a section of the structure of 55 Figure 4 taken upon the line 5-5.

In the drawing similar numerals indicate like parts.

The general uses of thermostatic valves are too well known and too well established to need anything more than the briefest statement: and my explanation of the utility of the device will therefore be confined to the special utility of the shower bath use by which it is here illustrated.

Notwithstanding the recognized value of 60 shower baths, their adoption by hotels and like places of public entertainment has been slow because of the dangers connected with their use. Carelessness in the opening of the valves or slow delivery of hot water at the 65 start, by which the mixture is not properly adjusted, excessive use of cold water by other users, lowering its pressure, or other causes may result in the scalding of the bather and a consequent suit against the proprietor of 70 the establishment. This danger and responsibility place a very high premium on quick and reliable thermostatic control of the temperature at which the water discharges.

My invention is directed to separate ther- 75 mostatic control of the water flowing in each path. In this case each shower bath comprises a separate path, but a bank of showers or other devices could, of course, be served by one valve, in either event rendering the 80 shower baths safe at all times for use.

The drawing is intended to illustrate a typical shower bath of the simplest form having hot and cold water inlets 5 and 6, controlled by valves 7 and 8 to supply water 85 through a riser 9 to a shower head 10. In showing my thermostatic valve 11 in the connection 12 close to the shower head it is not my intention to suggest that it must be located at this point as it can be inserted anywhere beyond the point at which the hot and cold water are mixed and entirely independently of whether or not an intermediate mixing chamber or hand-control valve, or both, be used between the hot and cold water valves 90 and my thermostatic valve.

Whether the piping be located in front of or behind the wall 13 is, of course, wholly immaterial.

My control valve comprises essentially a 100

casing 14 having an inlet 15, outlet 16 and interior valve opening 17 closed by a thermostatic element 18.

As required by the statute I have disclosed 5 the best form known to me in one location in which it is of great utility and am asking protection not only for the valve broadly but also for the valve in this location in which such a valve is so much needed.

10 In the first variation herein the interior valve 17 connects with a longitudinal passage 19 which is set off from the rear wall 20 by the arm 21 of a preferably U-shaped thermostatic valve element 22. This element is 15 secured to the front wall 23 by arm 24 and bolts 25. Leakage is prevented by packing 26, 27.

I find that the sensitiveness of the thermostatic element is greatly increased by extending the inlet 15' to a point near to the bend 20 of the thermostat U preferably also flattening it as seen in Figures 2 and 3 so as to apply the inlet hot water directly to the most sensitive part of the thermostat.

The casing provides longitudinally extending lateral walls 28, 29 which seal at the sides and back with the side edges of arm 21 and bend 30 of the thermostatic element 18. These walls are preferably finished so that the thermostatic element may move 30 transversely to the passage with variation in temperature without losing its effective seal.

The clearance between the side edges of the thermostatic element and the lateral walls 28 and 29 may be very slight so as to allow 35 but slight leakage of water between, with the result that the small volume of water beyond the valve will cool before it reaches the sprinkler, protecting against possible scalding. The shutting down of flow through the thermostatic control will cause the water in the casing to cool, hastening readjustment of flow to normal conditions.

In all of the above discussion I have considered the shower bath use of the valve from 45 the standpoint of protection against excessive temperatures because this is the type of protection which is most sought and which will likely be most used, but I recognize that the invention has utility also in this shower bath 50 use to prevent excessive flow of cold water which would be injurious, for example to patients in a sanitarium. This would require valve reversal merely in the illustration of 55 Figure 4, for example. If the inlet 17' were brought around to the opposite side of the element 18 in that figure the valve would close by contraction for this purpose.

With increase in temperature the arm 21 60 moves across the valve opening, and, at the predetermined temperature, comes in contact with a valve face which may be the rear wall or a rib 31 extending outwardly from the rear wall and engaging the side walls 28 and 65 29. Further closing movement of the arm

21 merely bends it without interfering with the effectiveness of its seal against rib 31.

I recognize that the thermostatic element need not be used to close the passage by lateral movement and have illustrated in 70 Figures 4 and 5 a construction in which a mere valve opening is closed from the face. It is, of course, open to the qualification that, when closed, the full water pressure assists in holding it closed; but with the advantage that, when nearly closed the water pressure will assist in closing it and will tend to "snap" it shut.

The passage 19' is closed off from the body 80 of the casing throughout the entire length of the body except at the passage opening 17' where it is capable of being closed by the side face of the thermostatic element.

Because of the necessity for access during 85 manufacture the casing is made in several parts which are welded or otherwise fastened together by flanges. I have shown these flanges as transverse for reasons of appearance only and with recognition of the fact that any convenient line of division may be 90 used which will give access to the interior for the purpose of finishing the sealing surfaces if desired, and to permit introduction of the thermostatic element. The fastening may be temporary or permanent.

As the thermostatic element is made of thin 95 resilient material there is no danger of injury from over-expansion of the element in either variation as the only effect of such over-expansion beyond the closing position is to bend the valve arm at intermediate points about the cooperating casing valve face. In Figures 4 and 5 any bending of the arm beyond the position of complete closure of the valve opening would tend to lift the outer end of the closure away from the face 32 of the passage opening, but this can be taken care of easily by providing for substantially 100 complete but not complete flow cut off at the desired temperature and for increasingly 105 complete closure from that point up to a designed maximum at which the thermostatic arm will make engagement with the face 33 of the passage inlet completing the closure. Slight movement beyond this position would merely slightly open the valve between the 110 arm and the face 32.

It will be evident that both variations of 115 my invention provide a valve in which the movable valve element is a thermostatic arm expanding toward and contracting away from position of valve closure; and that both 120 use the water pressure to some extent to snap the valve shut as the arm approaches position of full closure.

It will be further evident that the leakage 125 allowed in the variation of the earlier figures may be kept within any predetermined limits desired and may be used to assist in the resumption of normal flow conditions, both 130

by relieving the pressure when the arm closes the main opening and by allowing flow of part of the water to drip out through the shower head.

5 In view of my invention and disclosure variations and modifications to meet individual whim or particular need will doubtless becomes evident to others skilled in the art, to obtain all or part of the benefits of my invention without copying the structure shown, and I, therefore, claim all such in so far as they fall within the reasonable spirit and scope of my invention.

10 Having thus described my invention, what I claim as new and desire to secure by Letters Patent is:

15 1. In a protective device for shower baths, sources of hot and cold water supply, valves therein, a shower head, piping connections between the sources and head, a thermostatic valve of U-shape in the piping connections adapted to close off the water supply and receiving water delivery against the bend of the U.

20 2. In a protective device for shower baths, sources of hot and cold water supply, valves therein, a shower head, piping connections between the sources and head, a thermostatic valve in the connections comprising a casing having a valve opening and a thermostatic element of U-shape adapted to swing across the opening to reduce the area of the opening and ultimately to close the opening and a nozzle delivering the water supply against 25 the bend of the U.

30 3. In a protective device for shower baths, sources of hot and cold water supply, valves therein, a shower head, piping connections between the sources and head and a thermostatic valve in the connections comprising a casing having a rear wall and spaced side walls and a U-shaped thermostatic valve element adapted to seal against excessive leakage between it and the side walls and to 35 form a passage between said valve element and the rear wall and to seal against leakage between it and the rear wall with continued expansion of the thermostatic element.

40 4. A thermostatic valve comprising a casing having a rear wall and spaced side walls and a thermostat having a U-shaped arm adapted to seal against excessive leakage between it and the side walls in the closed position of the valve and to form a passage when the valve is open between the arm and the rear wall but to seal by its outer surface against leakage between it and the rear wall with continued thermal expansion 45 of the thermostatic arm.

50 5. A thermostatic valve comprising a casing having a fluid passage, an opening into the passage and a thermostat having a U-shaped arm adapted to seal against a wall 55 of the opening to seal the opening and an

inlet discharging water within the interior of the U and toward the bend of the U.

6. A thermostatic element having a resilient U-shaped valve arm adapted to bend when expanded beyond the intended position of valve closure, a casing and walls in the casing providing a passage and having an opening adapted to be closed by the arm. 70

7. A thermostatic element of U form having one arm of the U relatively flat and of resilient material, a casing and walls within the casing forming three sides of a passage of which the arm forms the fourth and for which passage the arm forms a closure. 75

8. A thermostatic control device comprising a casing containing a passage intended as an outlet passage for the casing, a U-shaped thermostat having an arm adapted to close the passage and an inlet for the casing applying the inlet liquid directly to the 80 inside of the bend of the U.

9. In a protective device for shower baths, sources of hot and cold water supply, valves therein, a shower head, piping connections between the sources and head, a thermostatic valve in the connections comprising a casing having a valve open at its side and end and a U-shaped thermostatic valve element having an arm closing the side and adapted to move across the end, sealing with the side 85 walls in the casing to protect against excessive leakage between the walls and the arm and a terminal for the connections within the casing delivering the water within the U-shaped valve element and near the bend of the U. 90
